UNITED STATES PATENT OFFICE.

ARTHUR C. FRIEDEL, OF SYRACUSE, NEW YORK.

WARDROBE.

Application filed May 17, 1923. Serial No. 639,540.

To all whom it may concern:

Be it known that I, ARTHUR C. FRIEDEL, a citizen of the United States of America, of Syracuse, in the county of Onondaga, in the 5 State of New York, have invented new and useful Improvements in Wardrobes, of which the following, taken in connection with the accompanying drawings, is a full, clear, and exact description.

10 This invention relates to a wardrobe in which the entire body including the four sides, bottom and top, and also including the door, are made of heavy cardboard re-enforced by relatively light wood frames and 15 all assembled in a manner hereinafter described for the purpose of producing a light yet strong and durable cabinet, capable of being manufactured at a comparatively low cost.

20 The main object is to provide a light and easily portable cabinet of this character which is practically dust and moth proof, and may be readily collapsed for storage or transportation.

25 Other objects and uses relating to specific structural features will be brought out in the following description.

In the drawings,

30 Figure 1 is a perspective view on a reduced scale, of a wardrobe cabinet embodying the various features of my invention.

Figure 2 is an enlarged vertical sectional view from front to rear, of the same cabinet, taken on line 2—2, Figure 1, the central portions being broken away.

35 Figure 3 is an enlarged horizontal sectional view taken on line 3—3, Figure 1, except the central portions are broken away, and Figure 4 is an enlarged horizontal sectional view taken on line 4—4, Figure 1, in the horizontal plane of the door lock.

40 Figure 5 is a perspective view of the main body collapsed and Figures 6 and 7 are perspective views of one of the detached end heads and the hanger bar respectively.

45 This cabinet is substantially rectangular and elongated vertically and comprises a single sheet of heavy paper cardboard or pasteboard of sufficient vertical height and 50 length to form the opposite upright side walls —1—, the rear wall —2— and front door stiles —3— integrally united, and scored at the four corners to permit the op-

posite side walls, rear wall, and door stiles to lie in substantially flat planes with the 55 opposite side walls parallel and the front stiles —3— also parallel with the rear wall —2—, the stiles —3— being of substantially the same width and relatively narrow as compared with the entire width of the front 60 of the cabinet to form a suitable door opening —4— whereby access may be had to the interior of the cabinet for storing goods therein and removing them therefrom.

The bottom wall —5— and the top wall 65 —6— are each made of a single sheet of similar heavy paper board of substantially the same form and area so as to be interchangeable, the bottom wall —5— being provided with integral downturned flanges 7—7—, of uniform vertical height along its marginal edges while the flanges —7— are disposed in planes at substantially right angles to that of the main body.

The form and area of the horizontal portion of the bottom wall —5— is substantially the same as that of the interior of the cabinet between the upright front, rear and side walls, and is therefore, rectangular and is scored along the junctions of the horizontal 75 portion with the upright flanges —7— to enable the latter to be easily bent downwardly for producing an inverted rectangular cup-shaped body adapted to be telescopically inserted within the lower ends of 80 the upright walls of the cabinet with the lower edges of the flanges in substantially the same horizontal plane as the corresponding lower edges of the upright walls.

85 The top wall —6— is provided with upturned flanges —8— along the four marginal edges of the horizontal portion thereof, and at right angles thereto, the area of the horizontal portion being substantially equal to that of the interior of the cabinet within the 90 upright side walls thereof.

This top wall —6— is also scored or creased at its junction with its flanges —8— to enable the latter to be easily bent upwardly, said flanges being substantially the 100 same height as the flanges —7— of the bottom —5— to form a cup-shaped member which is inserted telescopically between the upper ends of the side walls with the upper edges of the flanges —8— disposed in substantially the same horizontal plane as that 105

of the corresponding upper edges of the four side walls.

The bottom and top walls —5— and —6— are reinforced by rectangular frames —12— and —12'— of wood or other light but rigid material having lengthwise channels —13— and —13'— in which the marginal flanges —7— and —8— are respectively secured by glue or other suitable fastening means to form removable end heads for the cabinet, the channels of each frame being of sufficient width to receive the adjacent end edges of the rear and side walls —1— and —2— and stiles —3— when the parts are assembled for use.

This leaves extra channel spaces between the stiles across the top and the bottom of the door opening, which spaces are filled in by an extra lintel strip —10— and an extra sill strip —11— of the same material as the sides, secured by gluing or otherwise in said channels against the front faces of said flanges with their ends abutting against the inner edges of the stiles —3— and their free edges extending beyond the corresponding walls —5— and —6— to form lower and upper door stops.

The door consists of a single rectangular piece of flat paper board —15— of slightly greater area than the door opening —4— so that when secured in place, its marginal edges may overlap upon the outer faces of the upright stiles —3—, lintel piece —10— and sill piece —11— to completely close the opening.

The portion of the door plate —15— which is registered with the inner edge of one of the stiles, as the left hand stile, Figure 3, is scored or creased at —16— from top to bottom to form a flexible hinge connection between the main body of the door plate and that which is secured to the corresponding lintel whereby the door will be supported to swing freely to and from its closed position.

The portion of the door plate at the outside of the flexible portion —16— is secured to the outer face of the adjacent stile —3— by screws —17— or equivalent fastening means while the opposite or free upright edge of the door plate —15— closes against the outer face of the corresponding stile.

Suitable corner posts —18— of wood or equivalent material of substantially the same width as that of the stiles —3— are secured to the inner faces of said stiles by means of the screws —17— and are of substantially the same length as the distance between the bottom wall —5— and top wall —6— against which their lower and upper ends abut respectively and thereby, give additional support to the top and bottom walls.

As previously stated, the door plate —15— extends beyond the flexible hinge portion —16— so as to overlap upon the

outer face of the adjacent stile —3— and this portion of the plate is firmly held in place against said stile by a re-enforcing strip —20— of wood or equivalent material held in place by the screws —17—, said strip —20— being of substantially the same length as the distance between the bottom and top frames —12— so as to abut endwise against the upper and lower faces of said frames respectively.

A similar upright re-enforcing strip —20'— of wood or equivalent material is secured by screws or equivalent fastening means —17— to the outer face of the right hand stile —3—, Figure 3, just beyond the free edge of the door plate —15— and extends from the upper face of the lower frame —12— to the underside of the upper frame —12'— so that the two re-enforcing strips —20— and —20'— together with the inner re-enforcing strips —18— serve to stiffen the stiles and also to additionally support the lower and upper frames —12— and —12'— in parallel spaced relation thereby permitting the door to operate freely at all times. In like manner, the main body of the door plate —15— between the flexible portion —16— and free edge of the door is re-enforced by an inner marginal frame —21— and an outer marginal frame —22— both made of comparatively light strips of wood and secured to the inner and outer faces of the door plate by screws —23—.

These frames —21— and —22— follow the marginal edges of the door plate —15— a short distance from the corresponding edges thereof, sufficient to allow the frame —21— to swing between the inner edges of the re-enforcing strips —18— as shown in Figure 3, and also between the bottom and top frames —12— and —12'— and against the lintel and sill pieces —10— and —11—.

The lintel strip —10— and sill strip —11— are respectively re-enforced by cross bars —14— and —14'— of wood or equivalent light and rigid material resting loosely against the inner faces thereof and having their ends rabbeted to overlap upon the inner faces of the lower and upper ends of the corner posts —18—.

The ends of the cross bar at the hinged side of the door are secured to the adjacent posts —18— by screws —17'— while their opposite ends are detachably clamped to the corresponding posts by clamping bolts —18'— thereby holding the front edges of the side walls —2— and stiles —3— in fixed relation when the parts are adjusted for use.

A hanger bracket —26— is removably secured by nuts —26'— to the upper end head —6— and adjacent cross bar —14— and extends downwardly therefrom into the cabinet and partially across the door opening for supporting the front end of a forwardly and rearwardly extending guide bar —27—

having its rear end removably clamped to the rear wall —2— of the cabinet by a thumb nut —27'— for receiving and supporting a slide bar —28— upon which the 5 garment hangers (not shown) are mounted.

The side of the frame —21— nearest the free edge of the door also serves as a convenient support for a suitable lock —24— having a bolt —25— adapted to enter a suitable 10 keeper in the inner edge of the adjacent reinforcing member —18— as shown in Figure 4.

It will be noted that the main body of the cabinet consisting of the upright side walls 15 —1—, rear wall —2— and door stiles —3—, constitutes an upright rectangular tube having a door opening in one side and that the marginally flanged bottom and top walls —5— and —6— and their re-enforcing 20 frames —12— and —12'— constitute the end heads of the cabinet telescopically secured therein while the door plate secured along one of its upright edges to the tubular body at one side of the door opening and 25 having its longitudinal score or crease near said edge enables the door to swing about the score line as the hinge.

When the parts of the cabinet are assembled for use, the lower end frame —12— 30 rests upon the floor and supports the superstructure and when the door —15— is opened, the bar —28— with the garment hangers thereon may be drawn outwardly along the bar —27— and through the door 35 opening or returned wholly within the cabinet to permit the closing of the door.

On the other hand, when the cabinet is emptied, and it is desired to collapse the same for storage or transportation, it is 40 simply necessary to remove the bolts —18—, bracket —26— and hanger bar —27—, whereupon the upper end head —6— with its frame —12'— may be removed from the upper ends of the side walls —1— and —2— 45 and stiles —3—. The side walls and stile may be then withdrawn upwardly from the lower end frame —12— and its bottom wall —5— and, together with the door —15—, posts —18— and cross bars —14— and

—14'—, folded into compact form as shown 50 in Figure 5.

I claim:

1. A collapsible wardrobe cabinet of rectangular horizontal cross section comprising a single sheet of cardboard forming the 55 back, sides and portions of the front of the cabinet and scored at the four corners to permit the front portions to fold upon the sides and the sides to fold upon the back, lower and upper end heads having channels into 60 which the adjacent ends of the back, sides and front portions are inserted when the cabinet is adjusted for use, and a combined door and stile section of card board scored at the junction of the door and stile to form 65 a hinge, said stile, being secured to one of the first named front portions to support the door.

2. A wardrobe cabinet as in claim 1, in 70 which the channeled portions of each end head are made of wooden rails rigidly united to each other at the corners.

3. A wardrobe cabinet as in claim 1, in 75 which the free edge of the cardboard door section overlaps upon the adjacent front portion when the door is closed.

4. A wardrobe cabinet as in claim 1, in 80 which upright stiffening members of wood are secured to the inner faces of said front portions to form portions of the door stiles. 80

5. A wardrobe cabinet as in claim 1, in 85 which a rectangular frame of wood is secured to the door near the marginal edges thereof and at one side of the score line which forms the hinge for the door.

6. A wardrobe cabinet as in claim 1, in 90 which the channels of each end head are formed in a wooden frame and each head includes a cardboard panel having its marginal edges inserted in the channels of said frame.

In witness whereof I have hereunto set my hand this 10th day of May, 1923.

ARTHUR C. FRIEDEL.
